UNITED STATES PATENT OFFICE.

THOMAS B. LEPLEY, OF LA GRANDE, OREGON, ASSIGNOR OF ONE-HALF TO
H. RUHNSTROTH, OF SAME PLACE.

CAN-OPENER.

SPECIFICATION forming part of Letters Patent No. 511,959, dated January 2, 1894.

Application filed June 15, 1893. Serial No. 477,718. (No model.)

To all whom it may concern:

Be it known that I, THOMAS B. LEPLEY, a citizen of the United States, residing at La Grande, in the county of Union and State of Oregon, have invented a new and useful Can-Opener, of which the following is a specification.

The invention relates to improvements in can openers.

10 The object of the present invention is to improve the construction of can openers, to provide a simple, inexpensive and efficient one, and to enable a can to be readily opened without forcing the severed portion of the top 15 within the can.

The invention consists in the construction and novel combination and arrangement of parts hereinafter fully described, illustrated in the accompanying drawings, and pointed 20 out in the claims hereto appended.

In the drawings: Figure 1 is a perspective view of a can opener constructed in accordance with this invention. Fig. 2 is a detail perspective view of the knife. Fig. 3 is a similar view of the adjustable can-holder.

25 Similar numerals of reference indicate like parts in all the figures of the drawings.

1 designates a frame of approximately inverted U-shape, provided at the lower ends 30 of its sides with feet 2, which are secured upon a base 3, and having at its top cross-piece a centrally-located guiding sleeve 4, receiving a stem 5, of a knife 6, which is adapted to be raised and lowered by an operating lever 35 7 to sever, partially, the top of a can. The stem 5 has its upper end bifurcated and pivoted to the operating lever, which has one end shaped into a handle and its other end bifurcated and adjustably pivoted to an arm 8, and 40 the latter has its lower end provided with a foot 9 pivoted to the frame. The frame is constructed of flanged metal and is preferably T-shaped in cross-section; and the foot 9 is pivoted to the outer flange of the frame. 45 The upper end of the arm 8 is provided with a series of perforations 10, to receive the pivot 11, which connects the rear end of the operating lever to the arm to afford an adjustment.

The can-holder 12 is adjustably secured to 50 the sides of the frame. It has a central opening 12^a, extending inward from one of its

sides, and it is provided on its lower face at the back of the opening 12 with a depending curved flange 13, to form a guide for, and to receive the top or upper edge of a can.

55 The knife 6 is cylindrical and is provided with tapering cutting blades 14, having oppositely-inclined divergent cutting edges; and they are separated at their points by an approximately Y-shaped opening 15, which 60 causes an unsevered portion to be left between the blades to prevent the top of the can being forced inward. The unsevered portion remains until the blades 14 have finished cutting, or nearly so, and it is then cut by an inclined supplemental blade 16, arranged at the top of the Y-shaped opening and extending inward and adapted, when the knife is withdrawn or lifted, to carry with it the severed portion of the top of the can. The top of the 70 cylindrical knife is provided with a head 17, which is secured to the lower end of the stem.

75 It will be seen that the can opener is simple and comparatively inexpensive in construction, and that it is adapted to open cans rapidly and safely without forcing the severed portions within the cans.

Changes in the form, proportion, and the minor details of construction may be resorted to without departing from the principle or 80 sacrificing any of the advantages of this invention.

The adjustability of the can holder is obtained by series of parallel horizontal flanges 85 18, which receive the side edges 19 of the can holder. Any number of these horizontal flanges 18, which are arranged on the inner faces of the sides of the frame 1, may be provided and the can holder has at the front edges of the side edges 19 stop lugs 20 which 90 are formed integral with the can holder, and which prevent the same being moved rearward too far.

What I claim is—

95 1. In a can opener, the combination of a frame having vertical sides, a can-holder adjustably secured to the sides and having a knife-opening and arranged to engage the top of the can to secure the same upon the frame and provided at the back of the opening with a depending curved flange to form a guide for cans, and to support a can at the rear upper

edge thereof an arm pivoted to the frame, a lever fulcrumed on the arm, a stem pivoted to the lever and mounted on the frame, and a knife secured to and carried by the stem, substantially as described.

2. In a can opener, a cylindrical knife provided with opposite tapering blades having inclined diverging cutting edges, and having a Y-shaped space separating the blades and provided at the top of the space with an inclined supplemental blade extending inward, substantially as and for the purpose described.

3. In a can opener, the combination of a base, an inverted U-shaped frame secured to the base and provided at its top with a guiding sleeve, an arm provided at its lower end with a foot pivoted to one side of the frame, said arm extending upward above the frame, an operating lever adjustably connected to the arm, a stem arranged in said sleeve and connected to the operating lever, a knife secured to and carried by the stem, and a can-holder secured to the frame and arranged to engage the top of a can to secure the same

upon the base and provided with a knife-opening and having a depending curved guide-flange arranged at the back of the opening, substantially as and for the purpose described.

4. In a can opener, the combination of a frame having vertical sides and provided on the inner faces of the same with a series of horizontal flanges arranged in pairs, an adjustable can holder arranged to engage the top of a can to secure the same upon the frame and adapted to fit between the said flanges and provided at its front with stop lugs and having an opening and provided at the back of the same with a curved flange, and a vertically movable knife, substantially as described.

In testimony that I claim the foregoing as my own I have hereto affixed my signature in the presence of two witnesses.

THOMAS B. LEPLEY.
